UNITED STATES PATENT OFFICE.

HERMANN LEMP, OF ERIE, PENNSYLVANIA, ASSIGNOR TO GENERAL ELECTRIC COMPANY, A CORPORATION OF NEW YORK.

FUEL-PUMP.

1,166,230.

Specification of Letters Patent. Patented Dec. 28, 1915.

Application filed September 17, 1912. Serial No. 720,771.

To all whom it may concern:

Be it known that I, HERMANN LEMP, a citizen of the United States, residing at Erie, county of Erie, State of Pennsylvania, 5 have invented certain new and useful Improvements in Fuel-Pumps, of which the following is a specification.

This invention relates to internal combustion engines, and especially to those in which 10 liquid fuel is fed to the cylinders under pressure, and is ignited in the cylinders by the high temperature of air compressed therein to a heavy pressure. The object of the invention is to enable the speed of such 15 an engine to be regulated and maintained at or near constant speed by varying the quantity of fuel supplied to the cylinders. To this end I provide a fuel pump whose capacity can be varied by a speed responsive 20 device driven by the engine. The pump has a constant stroke and the fuel is delivered to it by a measuring device controlled by the speed responsive device.

In the accompanying drawings, Figure 1 25 is a side elevation showing certain parts in section; Fig. 2 is a front view; Fig. 3 is a section on the line 3—3, Fig. 1; Fig. 4 is a plan view; Fig. 5 is a side view of the plungers used to measure the oil; and Fig. 6 is 30 an end view of the same.

The engine has a speed governor 1 driven by the upright shaft 2 on which are two gears 3 and 4. The upper one engages a gear 5 on a shaft 6 which carries an eccentric 35 7 actuating a rocking frame 8. A cross-bar on said frame is provided with adjustable tappets, such as the set screws 9, which bear upon the upper ends of the pump plungers 10 and impart to them a downward 40 forcing stroke at each downward movement of said frame. Springs 11 lift the plungers when the frame moves upward. The pump illustrated has four plungers, but the number will vary to correspond with the number 45 of cylinders in the engine, each cylinder having its individual pump plunger.

The cylinders 12 in which the pump plungers work are supplied with fuel through ducts 13 leading down from basins 14, arranged in a row beneath a measuring device 50 which feeds predetermined quantities of fuel into them in accordance with the demands upon the engine. The measuring device which I prefer to employ consists of a

rotary multiple valve set in a casing in the 55 bottom of an oil tank 15 to which a supply of fuel is furnished through a pipe 16 controlled by a float valve 17.

The bottom of the tank has a cylindrical casing 18 open along its top and bottom and 60 arranged directly above and parallel with the row of basins 14. In said casing fits a cylinder 19 keyed upon a sleeve 19' on one end of which is a gear 20 meshing with the gear 4, so that said sleeve and cylinder rotate in synchronism with the governor shaft 2. In the sides of the cylinder 19 and spaced 90 degrees apart are four longitudinal 65 grooves 21 in each of which is a plunger 22. The grooves terminate at different points 70 along the cylinder, one over each of the basins 14. All the plungers extend out beyond one end of the cylinder and are attached to a disk 23. A spindle 24 runs centrally through the sleeve 19' and is secured to the 75 disk 23. At its other end it is engaged by a fork 25 on a bell-crank lever 26 which is linked to the arm 27 of the speed governor.

The operation is as follows: The speed governor shifts the plungers 22 in their 80 grooves so that the open portions 28 of said grooves between their ends and the ends of their plungers are longer or shorter, as the case may be. These portions 28 successively fill with oil as the cylinder 19 in its rotation 85 brings them up to the open upper part of the casing 18. The rotation of the cylinder then carries them downward, the charge of oil in each portion being trapped by the 90 wall of the casing until the open lower portion is reached, when the oil drops into its respective basin 14 and runs down the duct 13 to the corresponding pump plunger. The pump has a constant stroke but the plungers 10 can deliver to the engine cylinders only 95 the quantity of fuel supplied by the measuring device. If the load increases the falling governor weights will retract the plungers 22 and lengthen the open portions 28 of the grooves, so that more fuel will be fed 100 to the engines. The opposite effect takes place if the load drops off.

In accordance with the provisions of the patent statutes, I have described the principle of operation of my invention, together 105 with the apparatus which I now consider to represent the best embodiment thereof; and I desire to have it understood that the

apparatus shown is only illustrative, and that the invention can be carried out by other means.

What I claim as new and desire to secure 5 by Letters Patent of the United States, is:—

1. The combination with an internal combustion engine provided with a speed governor, of a fuel pump connected with a moving part of the engine having a constant 10 stroke, a conduit for fuel connected with said pump, a fuel tank above said conduit, and means controlled by the speed governor for transferring measured quantities of fuel varying with the load on the engine from said 15 tank into said conduit.

2. The combination with an internal combustion engine provided with a speed governor, of a fuel pump connected with a moving part of the engine having a constant 20 stroke, a conduit connected with said pump, a fuel tank above said conduit, a measuring device interposed between said tank and conduit for feeding charges of fuel by gravity into said conduit, and means controlled by 25 the speed governor for varying the quantity of each charge in accordance with the load on the engine.

3. The combination with an internal combustion engine provided with a speed governor, of a fuel pump connected with a moving part of said engine having a constant stroke, a conduit for fuel connected with said pump, and a rotary measuring device 30 geared to the speed governor shaft, and controlled by said governor, for positively conveying varying quantities of fuel to said conduit in accordance with the load on the engine.

4. The combination with an internal combustion engine provided with a speed governor, of a fuel pump connected with a moving part of said engine having a constant stroke, a conduit for fuel connected with said 40 pump, a fuel tank, a constantly rotating valve in the bottom of said tank, and means controlled by the speed governor for causing said valve to measure out varying supplies of fuel into said conduit in accordance with the load on the engine.

5. The combination with an internal com-

bustion engine provided with a speed governor, of a fuel pump connected with a moving part of said engine having a constant stroke, a fuel tank, a constantly rotating cylindrical valve in the bottom of said tank 55 having longitudinal grooves for feeding fuel to said pump, and means controlled by the speed governor for varying the length of the open portions of said grooves.

6. The combination with an internal combustion engine provided with a speed governor, of a fuel pump connected with a moving part of said engine having a constant stroke, a fuel tank, a constantly rotating cylindrical valve in the bottom of said tank 60 65 having longitudinal grooves for feeding fuel to said pump, plungers movable lengthwise in said grooves, and connections between said plungers and the speed governor of said engine.

7. The combination with an internal combustion engine, of a fuel pump comprising a cylinder and a piston, means connecting with the moving part of said engine for imparting a stroke of constant length to the piston, 70 a source of fuel supply, a measuring device for transferring measured quantities of fuel from said source to the cylinder, and a governor for regulating the action of said measuring device in accordance with the speed of 75 said engine.

8. The combination with an internal combustion engine provided with a speed governor, of a fuel pump having its plunger connected with a moving part of said engine 80 and having a constant length of stroke, a conduit for conveying fuel to the suction side of said pump, a measuring pump also driven by the engine for discharging measured quantities of fuel to said conduit, a governor 85 for the engine, and regulating mechanism for said measuring pump controlled by said governor.

In witness whereof, I have hereunto set my hand this thirteenth day of September, 95 1912.

HERMANN LEMP.
